UNITED STATES PATENT OFFICE.

WILLIAM ROSCOE TUCKER, OF DAWSONVILLE, GEORGIA.

PROCESS OF MOLDING FACED CONCRETE UNITS.

No Drawing.

Application filed November 22, 1926. Serial No. 150,151.

This invention relates to the process of molding faced concrete units by partly submerging the aggregate in mercury before pouring the body of the units, and has for its objects, first, the elimination of the necessity of cleaning the units, second, the introduction of a more artistic class of facings, and third, the production of facings that are as permanent as the units themselves.

Since the use of mercury constitutes the principal feature of this process, it is important that the part of the mold coming in contact with the mercury be made of iron, or of such other material as will not alloy with or contaminate the mercury, and since mercury, being a heavy liquid, tends constantly to adjust its surface to a horizontal plane, it is important that the mold be placed in a level position, and remain undisturbed until the unit is entirely solid.

In this process the aggregate is arranged on the bottom of the mold just as it is to appear in the face of the finished unit, and mercury is carefully poured into the mold until it submerges the portion of the aggregate that is to show when the unit is finished.

If the aggregate used is not sufficiently heavy to cause the desired submergence without floating or moving, it should be weighted down by a second layer of aggregate, or lightly attached to the bottom of the mold by means of a coating of gum, glue or wax applied to the bottom of the mold.

In order to strengthen the union between the concrete mixture and the aggregate, and to drive out the air from around the aggre-

gate, water is sprayed over the unsubmerged portion of the aggregate at this stage of the process, until it forms a shallow layer upon the mercury, unless it is found that the fluidity of the concrete mixture renders the addition of water unnecessary, in which event the concrete mixture is carefully poured next following the pouring of the mercury, the mold is filled, and the mass is left to harden.

When the unit has hardened sufficiently to withstand handling the vertical part of the mold surrounding the unit is separated from the bottom part of the mold containing the mercury, by inserting an edged instrument between the two parts of the mold, the unit is slowly lifted upward, and its curing continued in the usual manner. The mercury, draining clean from the face of the unit, remains in the bottom part of the mold, and may be used over and over, indefinitely.

This process gives facings that require no cleaning. The joints thus obtained are remarkably smooth and evenly sunken, giving the unit an unusually artistic appearance. And since the concrete mixture completely surrounds and encases all portions of the aggregate not submerged in mercury, facings thus produced are most lasting.

I claim:

The process of molding faced concrete units which consists in placing aggregate in the bottom of a mold, pouring in sufficient mercury to partly submerge the aggregate and filling the mold with a concrete mixture.

WILLIAM ROSCOE TUCKER.
